UNITED STATES PATENT OFFICE.

GARFIELD A. WOOD, OF DETROIT, MICHIGAN.

TRUCK-BODY-DUMPING MECHANISM.

1,271,975.

Specification of Letters Patent.

Patented July 9, 1918.

Application filed January 15, 1917. Serial No. 142,406.

To all whom it may concern:

Be it known that I, GARFIELD A. Wood, a citizen of the United States, and residing at Detroit, in the county of Wayne and State 5 of Michigan, have invented a new and Improved Truck-Body-Dumping Mechanism, of which the following is a specification.

The present invention relates to hydraulic (oil) hoisting means whereby the front ends 10 of truck bodies are lifted for dumping purposes, and its object is to provide a construction which is cheaper than existing devices and one which is particularly suitable for light trucks, although not limited thereto. 15 It consists in means whereby the upper end of the cylinder is braced; in a split clamping member extending around the cylinder at an intermediate point in the length thereof and receiving the upper ends of the brace 20 rods; in an improved head construction for the cylinder; in means connecting said clamping member and said head construction for retaining the latter in place; in means whereby the cylinder and hollow piston 25 rod which constitute the oil reservoir may be filled to a high level through a single port; in control means for hoisting means mounted on the clamping member whereby the operation of the device may be controlled 30 by a driver sitting on the seat; and in various other details of construction shown, described and claimed.

In the drawings, Figure 1 is a fragmentary side elevation, parts being broken away, showing one embodiment of the invention. Fig. 2 is a view corresponding thereto looking backwardly from a plane 35 just behind the vehicle seat. Fig. 3 is a fragmentary front view of the hoisting cylinder and support. Fig. 4 is a central section, looking from the right in Fig. 3. Fig. 5 is a section on the line 5—5 of Fig. 4. Fig. 6 is a fragmentary side view, parts being broken away, showing a modification 40 in which a single hoisting cable is used.

1 indicates the side bars, 2 the body pivoted to swing vertically about horizontal pivots located near the rear end thereof, 3 the driver's seat, 4 the upright hoisting cylinder, the base 5 of which is supported

from the side bars through the medium of a suitable cross frame preferably formed of angle-irons 6 to which the base is bolted. The upper end of the cylinder is braced from the outer ends of the front angle-iron 55 6 by means of tension rods 8 (having nuts 9 on each end and suitable lock washers or the equivalent if desired) whose upper ends preferably pass through holes in the rear half 11 of a clamping element that includes 60 a front half 12 and the connecting bolts 13 and conforms to a circumferential groove 15 cut in the outer surface of the cylinder.

The upper end of the cylinder receives a hollow head 16 which may have circumferential flanges 18 and 19 conforming to the inner surface of the cylinder and may be machined out circumferentially to receive suitable packing 20 which, when the head is drawn downwardly as hereinafter 65 described, allows a metal-to-metal contact between the head and the end surface of the cylinder and seals the joint. A hollow piston rod 22, having a piston 23, slides up and down through the head and through a packing plate 24 that has an annular depending flange 25 arranged to project into and compress packing 26 in the upper inner portion of the head 16 to insure a tight joint between the latter and the piston rod. The 70 packing plate is drawn down upon the head by means of the nuts 27 on the bolts 28 and 29, spaced diametrically from each other, the former being threaded into a boss 30 on the member 11 and the latter into a 75 boss 31 on an upward extension of the member 12.

Extending crosswise through the projecting end of the piston rod is a pivot bolt 33 upon which is supported an equalizing cross-bar 34 having pulleys 35 suspended from its outer ends. Cables 36, secured to the lower ends of the depending body arms 38 of the body 2, pass over the corresponding pulley and have their inner ends bent 90 around the corresponding clamping bolt 13 and secured in place by suitable shackles 39.

Depending from the front cross-bar 6 is an angle iron 40 upon one side of which is mounted a gear pump 41 (preferably that 100

shown and claimed in my application for patent Serial Number 14,479, filed March 15, 1915) that is driven from a longitudinally extending shaft 42 of the vehicle 5 in any suitable manner, for example, by the sprocket gears 43 and 44 (the latter being mounted on the opposite side of the member 40), the chain 45, the clutch pins 46 and the clutch member 48 carried by the propeller 10 shaft 42 of the vehicle. The clutch pins 46 are slidable longitudinally through the gear 44 through the medium of yoke arms 50 and the actuating arm 51 rigid with the shaft 52 which is mounted in the lower ends of member 40 and a companion member 53. The 15 specific construction described in this paragraph is claimed in my application for patent Serial Number 135,797, filed December 8th, 1916, and may be varied widely. In 20 some instances the pump may be driven by a countershaft as shown in my application for patent Serial Number 142,405, filed January 15, 1917.

In the present instance, however, the link 25 55 to which the arm 51 is connected is pivoted at 56 to a hand lever 58 that is itself pivotally supported at 59 on the front face of the member 12. Any suitable means is employed for limiting the throw of the hand 30 lever in each direction. A similar connection, consisting of the hand lever 60 and link 61 constitutes an actuating means for the valve arm 62 of the pump.

In order to allow the use of the interior 35 of the cylinder above the piston as a reservoir for oil, the cylinder is provided with a port 64 in the groove 15 opposite the member 12 and the latter is provided with a passage 65 with which the suction pipe 66 which 40 leads to the pump is connected by a packing gland 68. A sealing washer 69 is interposed between the member 12 and the cylinder. From the pump the oil is delivered through 45 the pipe 70 and passage 71 (Fig. 4) to the space beneath the piston. The interior of the piston rod is also used as a part of the reservoir, holes 72 (preferably cored out in the piston 23, thus avoiding any drilling of the piston rod 22) (Fig. 4) being provided 50 to allow ingress and egress of the liquid. At its upper end the piston rod is preferably closed by a diaphragm 73 and is perforated at 74 to admit air when the piston rod has risen a short distance whereby a tight seal is 55 secured and the partial vacuum which would otherwise obtain in the rod is broken in the general manner shown and claimed in my application for patent Serial Number 14,480, filed March 15, 1915. The upper end of the 60 piston rod might in some cases be left open as the cross-bar 34 would exclude foreign objects, but the tendency for the oil to slop over as the piston sinks would be objectionable.

Considering those features of cylinder 65 and piston rod construction thus far described, it will be seen that it would not be possible to fill that portion of the cylinder above the single port 64 by pouring liquid through said port. It would also be objectionable to pierce the cylinder at a higher level, and the head 16 and packing plate 24 could not well be pierced to allow the escape of the trapped air. In order to avoid these objections and at the same time provide a 70 75 cheaper construction, the piston rod is pierced at a point located above the upper edge of the piston a distance less than the distance from the port 64 to the lower surface of the head 16 as indicated at 76. The 80 cylinder and piston rod being filled in an obvious manner to the level of the upper edge of the port, it is then only necessary to work the pump to elevate the piston until it reaches the lower edge of the port 64, remove the plug 78 for an upward extension 79 of the passage 65 in the member 12 and pour in additional oil to cover the port to a depth sufficient to prevent air from being drawn into the suction pipe 66, in which operation the air will escape through the passage 76 (which would then be just below the head 16), the interior of the piston rod, and the passage 74 and allow the oil to rise 85 as high as the entrance to the passage 79 if 90 desired.

The pulley 35 may be mounted in different ways—preferably, however, its shaft 80 extends through the ends of a U-shaped strap 80' that is secured to an eye-bolt 81 by a nut 82. A cable guide 83 of pressed metal is interposed between the nut and the strap as best shown in Fig. 3.

As shown in Fig. 6, the cables 36 may be replaced by a single cable 85 which passes 105 along the under side of the member 86' (that corresponds to the member 11) from side to side partly in a groove, thus avoiding the use of the shackles 39.

From the foregoing it will be understood 110 that liquid may be either drawn from the reservoir through the suction pipe 66 and discharged through the pipe 70 for lifting purposes, or may be by-passed from the pipe 70 to the pipe 66 for lowering, or may be circulated continuously within the pump casing, as described in my application Serial Number 14,479, referred to above.

The details of construction may be varied 115 within wide limits without departing from the spirit of the invention, and I do not, therefore, wish to be limited except as indicated by the subjoined claims.

I claim:—

1. A motor vehicle comprising a frame, a 125 body pivoted to tilt thereon, an upright hoisting cylinder forward of the front end of the body, a piston and piston rod recipro-

cable therein for tilting said body, clamping means split transversely of the cylinder and encircling the latter somewhat below the top, a pump for delivering liquid into the space below the piston to elevate the latter, and a controlling lever for said pump mounted on said clamping means.

2. A motor vehicle comprising a frame, a body pivoted to tilt thereon, an upright hoisting cylinder forward of the front end of the body for tilting said body, said cylinder having a base, a cross-frame constituting supporting means for the base of the cylinder, said cylinder having a circumferential groove at a point considerably above the base and below the top, a split clamping element in said groove, and braces extending from the clamping element downwardly, forwardly and laterally to the outer ends of the cross-bar.

3. A motor vehicle comprising a frame, a body pivoted to tilt thereon, an upright hoisting cylinder forward of the body, a piston and piston rod reciprocable in said cylinder, means associated with the upper end of said piston rod for tilting the body, a clamping element associated with the upper portion of the cylinder, means for forcing the clamping element transversely of the cylinder into clamping relation therewith, a pump for delivering liquid to the space below the piston, a driven shaft, means for driving the pump from the shaft, said means including clutch mechanism and controlling means therefor, said controlling means including a hand lever supported on the clamping element.

4. A motor vehicle comprising a frame, a body pivoted to tilt thereon, an upright hoisting cylinder forward of the body, a piston and piston rod reciprocable in said cylinder, means associated with the upper end of said piston rod for tilting the body, a clamping element associated with the upper portion of the cylinder, means for forcing the clamping element transversely of the cylinder into clamping relation therewith, a pump for delivering liquid to the space below the piston, a driven shaft, means for driving the pump from said shaft at will, a valve for controlling the flow of liquid to the cylinder, and valve actuating means including a hand lever mounted on the clamping element.

5. A vehicle comprising a frame, a body pivoted to tilt thereon, an upright hoisting cylinder forward of the body, a piston and piston rod for the cylinder, a cross-arm connected to the upper end of the piston rod and extending transversely of the frame, sheaves supported on said cross-arm in a substantially vertical plane transversely of the frame, cable means passing over said sheaves and attached to the front portion of

the body, means encircling the upper portion of the cylinder, said cable means being arranged to operatively engage said encircling means substantially in the transverse central vertical plane of the cylinder.

6. A motor vehicle comprising a frame, a body pivoted to tilt thereon, an upright hoisting cylinder forward of the body, a piston and piston rod for the cylinder, a cross-arm connected to the upper end of the piston rod and extending transversely of the frame, sheaves supported on said cross-arm in a substantially vertical plane transversely of the frame, means encircling the upper portion of the cylinder, a single cable passing over said sheaves and connected to the front portion of the body, said cable being arranged to transmit stress to the encircling means.

7. A motor vehicle comprising a frame, a body pivoted to tilt thereon, an upright hoisting cylinder forward of the body, a piston and piston rod for the cylinder, a cross-arm connected to the upper end of the piston rod and extending transversely of the frame, sheaves supported on said cross-arm, means encircling the upper portion of the cylinder, a single cable passing over said sheaves and connected to the front portion of the body, said cable engaging with the encircling means substantially in the central vertical transverse plane of the cylinder and passing circumferentially about the cylinder from one side to the other.

8. A vehicle including a frame, a body pivoted to tilt thereon, an upright cylinder supported on said frame forwardly of the body, a piston and piston rod reciprocable in said cylinder, means associated with said piston rod for tilting the body, a split clamping member encircling the upper portion of said cylinder and mounted in a groove formed in the latter, means leading downwardly, forwardly and laterally from said clamping member for bracing the cylinder, a head for said upper end of the cylinder, and bolts associated with said split clamping member whereby said head is retained in position.

9. A vehicle comprising a frame, a body pivoted to tilt thereon, an upright hoisting cylinder forward of the body, a piston and piston rod for the cylinder, a cross-arm pivotally connected to the upper end of the piston rod to swing about an axis which extends longitudinally of the vehicle, said cross-arm extending transversely of the frame, sheaves supported on said cross-arm in the transverse central substantially vertical plane of the cylinder, cable means passing over said sheaves and attached to the front portion of the body, means encircling the upper portion of the cylinder, said cable means being arranged to operatively engage

said encircling means substantially in the transverse central substantially vertical plane of the cylinder.

10. A vehicle comprising a frame, a body pivoted to tilt thereon, an upright hoisting cylinder forward of the body, a piston and piston rod for the cylinder, a pair of sheaves supported by the piston rod, the axes about which said sheaves rotate extending longi-

tudinally of the vehicle, cable means passing over said sheaves and attached to the front portion of the body, means encircling the upper portion of the cylinder, said cable means engaging the encircling means on opposite sides of the central longitudinal vertical plane of the vehicle.

GARFIELD A. WOOD.
